W. H. COOPER,
OIL WELL APPARATUS,
APPLICATION FILED MAY 2, 1918.

1,272,625.

Patented July 16, 1918.

UNITED STATES PATENT OFFICE.

WALDREN H. COOPER, OF SISTERSVILLE, WEST VIRGINIA.

OIL-WELL APPARATUS.

1,272,625.

Specification of Letters Patent.

Patented July 16, 1918.

Application filed May 2, 1918. Serial No. 232,127.

To all whom it may concern:

Be it known that I, WALDREN H. COOPER, a citizen of the United States, residing at Sistersville, county of Tyler, and State of 5 West Virginia, have invented certain new and useful Improvements in Oil-Well Apparatus, of which the following is a specification.

My invention relates to oil well apparatus, and is adapted for use in connection with the usual type of oil well pump which, generally speaking, embodies an outer casing and an inner tube through which oil and gas are induced to flow from the oil bearing 15 sand by means of a working valve operated by suitable mechanism.

Heretofore, it has been the practice to connect a vacuum line to the outer casing in order to recover gas collecting therein, 20 but this practice has resulted in considerable valve trouble, necessitating cessation of the pumping operations and the pulling of the tubing and repairing of valves, with a view of endeavoring to rectify the trouble. 25 Apart from the inconvenience and expense involved in so doing, air would inevitably become present in the gas in sufficient quantities to seriously interfere with the making of the gasoline. Air would also leak 30 through the joints of the tubing into the casing, and obviously so in view of the casing being under a vacuum and atmospheric pressure existing in the tubing. This difference in pressure placed an additional burden upon the valves and involved additional work in an endeavor to equalize the fluid levels in the casing and tubing, which was relatively higher in the former, and 35 due to this condition valve trouble resulted. 40 The principal objects of my invention are to provide means for placing the tubing under a vacuum as well as the casing, preferably equalized in terms of inches, whereby the above recited disadvantages are wholly 45 eliminated and the efficiency and utility of the well apparatus therefore materially increased; and to provide separating means ancillary to the aforesaid means designed to increase the saving in gas and to advantageously separate gas from the oil for the 50 making of gasoline in a more economic and convenient manner.

These, together with such other objects as will hereinafter appear or are incident to 55 my invention, I attain by means of a con-

struction illustrated in preferred form in the accompanying drawings, wherein—

Figure 1 illustrates my invention applied to an oil well pump, the vacuum separating tank being adapted for use with wells 60 situated at an elevation in hilly country; and Fig. 2 is a modification of the separating means where the well is located in level country.

Referring to Fig. 1 of the drawings, 3 65 indicates the outer casing and 4 the inner tubing of the pump, the latter being provided with a barrel 5 designed to reach down to the oil bearing sand and having a working valve 6, of any desired construction, 70 adapted to be reciprocated in the barrel 5 by means of a sucker rod 7. The inner and outer chambers of the pump are respectively designated by the numerals 8 and 9. 10 is a vacuum line designed to be associated at its outer end with any suitable 75 vacuum mechanism, as a vacuum pump (not shown), and whose inner end extends into the head 11 of the casing and communicates with the chamber 9, in order to recover 80 whatever gas may collect in said chamber. As already indicated, such construction represents present practice in the oil well industry, and as such has been provocative of considerable valve trouble to 85 which attention has already been directed.

In carrying out my invention, I provide a vacuum line 12 whose inner end is associated with the extension 8^a of the tubing 8 at a point just below the stuffing box 13 90 which then constitutes the head of the tubing. This extension 8^a extends upwardly through the head 11 and has a tight fit in it. The pipe section 14 forms part of the vacuum line 12 and is connected at 14^a with 95 the vacuum line 10. The reference numeral 15 designates a separating tank whose upper end is interposed in the suction line 12 and is provided, if desired, with a safety valve 16. 100

From the above construction it will be apparent to those skilled in the art that in the event of a suction or pull being exerted in vacuum lines 10 and 12, both being connected to the same vacuum forming device, 105 that such suction or pull will simultaneously be effective and equalized in chambers 8 and 9 of the well, and thereby simplify and render more easy the operation of the working valve 6 when actuated. Upon actuation of 110

the valve any gas collecting in chamber 9 will be carried along line 10, and at the same time the oil, and gas with it, will flow upwardly through the tubing 8 and thence 5 horizontally through the vacuum line 12 into the tank 15, whereupon the gas rising to the upper portion of the tank will be carried along the conduit 14 and join with the gas which has been carried through the 10 line 10 in a direction toward the vacuum forming device. If there is any water present with the oil it will find its own level at the bottom of tank 15 with the oil superposed upon it, and suitable means may be 15 provided to discharge or carry off in separate conduits the oil and water thus separated.

In connection with the means for withdrawing the oil, and also the water if there 20 be any, I provide means effective during such withdrawal designed to maintain the vacuum in the tank and to offset the action of the vacuum with respect to such withdrawal, said means comprising an oil discharge pipe 17 which extends from the oil 25 charge pipe 17 which extends from the oil level downwardly to a drain 18 and thence upwardly, as 19, to form an oil seal, and in a similar manner I provide the water outlet pipe 20, which in turn has embodied with it 30 a drain 21 and an upwardly extending pipe 22, thus forming a water seal, the outer end of said pipe 22 preferably being formed with an adjustable swing pipe outlet 23, both of said discharging means being of 35 such length as to overcome the action of the vacuum by providing a slug of oil and water in the respective seals upon which the vacuum would have no lifting effect. In Fig. 1 of the drawings, I have indicated the 40 preferred lengths of outlet pipes expressed in terms of feet, and this is true in the case of the modification illustrated in Fig. 2, in which the tank is formed in two parts, connected by an intermediate pipe 24, the upper 45 part 15^a being interposed as before in the suction line 12, and the lower part 15', which receives the oil, and water if there be any, is provided with the oil outlet 17^a and water outlet 20^a, the modification being 50 adapted for wells located in level country, and if desired, may be associated or supported against the usual derrick structure.

By maintaining a vacuum in the vacuum 55 separating tank, a greater percentage of gas is liberated from the oil, and this together with the gas that was already available in both the chambers 8 and 9 are thus collected for utilization in the manufacture of gasoline in an advantageous and economical 60 manner, and this supply of gas may be readily increased by placing in the tank a heating coil 25. The principal object, however, of my invention is the equalization thus provided for in both the chambers 8 65 and 9, and the consequent equalization of

the oil level with reference to said chambers and the elimination of valve troubles and leakage from one chamber to the other. In the event that the oil flows through the casing 3, a by-pass 25 may be provided to connect the lines 10 and 12, and this by-pass is normally closed by the valve 26. The numeral 27 designates a valve in line 10 which, when the by-pass is intended to be used, may be closed and the valve 26 opened. In such 75 case the casing and tubing are both directly connected as a suction medium to the tank 15, the gas collecting in the tank being carried along pipe 14 and thence to the suction forming device as before. I may also provide the suction line with a check valve 28 in order to prevent back-flow into the separating tank 15 upon any temporary cessation 80 of the operation of the vacuum forming device.

What I claim is:

1. The combination of an oil well pump, a suction line serving to conduct a flow of oil and gas therefrom, and means associated with said line for separating the oil from 90 the gas, said line operative as a pressure reduction means for said pump.

2. In oil well apparatus, the combination of a pump, an oil and gas conducting line leading from said pump, means connected 95 with said line for maintaining a vacuum in said pump, and means for separating the oil from the gas in said line.

3. The combination with an oil well pump, of a vacuum line leading therefrom, 100 one part of said line constituting an oil and gas conductor, and a separator therefor, the other part of said line serving as a conductor for the separated gas.

4. The combination with an oil well 105 pump, of a vacuum line leading therefrom, one part of said line constituting an oil and gas conductor, and a separator therefor, the other part of said line serving as a conductor for the separated gas, said line operative 110 as a pressure reduction means for the pump and said separator.

5. The combination with an oil well pump, of pressure reducing means therefor including a vacuum line adapted to conduct 115 a flow of gas and oil from said pump, a separator tank interposed in said line and designed to separate and receive the oil from said line, and means for applying heat to the oil in said tank.

6. The combination of an oil well pump having inner and outer chambers, and pressure equalizing means for said chambers comprising a suction line organized to conduct gas and oil from said pump.

7. The combination of an oil well pump having inner and outer chambers, and pressure reduction and equalizing means therefor embodying a vacuum line connected with said chambers, part of said line constructed 130

and arranged to conduct a flow of gas and oil from one of said chambers.

8. The combination of an oil well pump having inner and outer chambers, and pressure reduction and equalizing means therefor embodying a vacuum line connected with said chambers, part of said line constructed and arranged to conduct a flow of gas and oil from one of said chambers and 10 provided with means for separating the oil from the gas.

9. The combination of an oil well pump having a plurality of chambers, pressure reduction means for said chambers comprising a two-part suction line leading to said 15 pump, and an oil receiving tank in said line.

10. The combination of an oil well pump having a plurality of chambers, pressure re-

duction means for said chambers comprising a two-part suction line leading to said 20 pump, and an oil receiving tank in said line, and means for procuring a discharge of oil from said tank.

11. The combination with an oil well pump, of a pressure reduction and equalizing means therefor embodying a vacuum line 25 wherein suction is employed to conduct a flow of liquid and gas from said pump, a vacuum separating tank interposed in said line and operating to receive the fluid from 30 said line, and tubular means constructed to conduct the separated fluid from the tank without impairing the vacuum maintained in the line and tank.

WALDREN H. COOPER.
